UNITED STATES PATENT OFFICE

2,569,716

MOBILE PARTS ORDER PAD HOLDER

Blaine W. Hawk, Sharpsville, and Frank S. Shannon, Sharon, Pa.

Application November 19, 1948, Serial No. 61,004

3 Claims. (Cl. 211—2)

1

This invention relates to movable supports, and more particularly to a movable and adjustable pad support device for use in taking inventory of automobile parts and similar merchandise stacked in bins.

A main object of the invention is to provide a novel and improved adjustable table device for supporting an order pad or the like during the process of counting parts or merchandise stacked in bins, whereby the pad may be supported in an elevated position when the upper bins are being examined and in lower positions when the lower bins are being examined, said device being simple in construction, easy to manipulate, and reducing the possibility of making errors in counting and recording the amount of parts or other merchandise in the various bins.

A further object of the invention is to provide an improved mobile adjustable pad-supporting table for use in taking inventory or in otherwise tabulating merchandise stacked in bins, said table being sturdy in construction, light in weight, inexpensive to manufacture, and foldable to a compact size when not in use.

Further objects and advantages of the invention will become apparent from the following description and claims, and from the accompanying drawings, wherein:

Figure 1 is a front elevational view of an order pad-supporting table constructed in accordance with the present invention, shown in folded position;

Figure 2 is a side elevational view of the table of Figure 1;

Figure 3 is a top plan view of the table of Figure 1;

Figure 4 is an enlarged fragmentary cross-sectional detail view taken on line 4—4 of Fig. 1;

Figure 5 is an enlarged cross-sectional detail view taken on line 5—5 of Figure 2;

Figure 6 is an enlarged cross-sectional detail view taken on line 6—6 of Figure 7;

Figure 7 is a view similar to Figure 2, but showing the step element of the table in operative position;

Figure 8 is a cross-sectional view taken on line 8—8 of Figure 7;

Figure 9 is an enlarged cross-sectional detail view taken on line 9—9 of Figure 8;

Figure 10 is a view similar to Figure 7, but showing the pad-supporting element in its lowered position.

Referring to the drawings, 11 designates a vertical rectangular frame structure comprising the vertical rear corner angle bars 12, 12 and the ver-

tical forward corner angle bars 13, 13, the rear angle bars 12, 12 extending higher than the forward angle bars 13, 13. Secured to the top ends of the corner angle bars 12, 12 and 13, 13 is an inclined rectangular frame 14 constructed of angle bars having inwardly-directed top flanges 15. Rigidly secured to the corner angle bars at the sides of the frame structure 11 are the horizontal angle bars 16, 16 located at the upper intermediate portion of said frame structure, as shown in Figures 1 and 2. Secured in the lower intermediate portion of said frame structure is a horizontal rectangular frame 17 constructed of angle bars having inwardly-directed top flanges, shown at 18. The vertically disposed angle bars 12, 13, the horizontally disposed angle bar 16, and the rectangular frame 17 cooperate to form a pair of upstanding spaced side frames connected together by cross bars extending therebetween. Secured to the side elements of frame 17 at its rear portion is a transverse horizontal bar 19. Hinged to the front element of frame 17 at 20, 20 is a step member 21 comprising a top frame 22 having the depending legs 23, 23 secured to its forward corners. Secured in overlying relation to top frame 22 is a rigid panel 24 provided with a covering of rubber 25, or of other suitable tread material. The ends of the legs 23 are provided with caps 26 of rubber or the like, as shown in Figure 6. The step member 21 may be positioned as shown in Figures 7 and 10, so that it provides an elevated support at the front of frame structure 11, or may be swung to an inoperative housed position within the frame structure, as shown in Figures 1 and 2, wherein it rests in inverted position on the transverse bar 19.

Designated at 27 is a rectangular tray having a handle 28 secured to the intermediate portion of its forward wall. Pivotally secured to the rear end portions of the side walls of tray 27 are respective link bars 29, which are pivotally connected at their lower ends to the intermediate portions of the side bars 16, as shown at 30. As shown in Figures 1 and 2, tray 27 normally overlies and is supported on the top frame 14. Said tray is provided at its under surface adjacent its forward wall with a hinged leaf 31. The tray may be supported in a horizontal position, as shown in dotted view in Figure 7, by swinging leaf 31 downwardly so that it bears on top frame 14, as shown in dotted view in Figure 7. Said tray may also be swung forwardly and downwardly to an inclined position, as shown in dotted view in Figure 10, wherein the handle 28 abuts

the rubber pad on step member 21 and frictionally holds the handle against outward slipping. Finally, the tray 27 may be swung to a horizontal position, shown in full line view in Figure 10, wherein it is supported on the step member 21. The tray may therefore be arranged in any one of four different positions, as follows:

1. The normal upper inclined position shown in full line view in Figures 1, 2 and 7.
2. The upper horizontal position shown in dotted view in Figure 7.
3. The lower inclined position shown in dotted view in Figure 10.
4. The lower horizontal position shown in full line view in Figure 10.

With the device arranged as shown in Figure 1, the tray may be employed to support an order pad, inventory pad, or various items of merchandise, where the person checking the items may reach the shelves on which they are located in a normal standing position. When items on higher shelves must be reached, the step member 21 is swung outwardly to the position shown in Figure 7, and is employed as an elevated support for the person checking the items. When thus employed, the tray 27 may be left either in its normal position or may be placed in its elevated horizontal position shown in dotted view in Figure 7. When items in lower shelves are to be checked, the device is arranged as shown in Figure 10, with tray 27 either in the lower inclined position shown in dotted view in said figure, or in the lower horizontal position shown therein.

The lower ends of the vertical corner posts 12, 12 and 13, 13 are provided with casters 32, enabling the device, in its folded position shown in Figures 1 and 2, to be readily moved to the location at which it is to be used.

The device enables the order pad or inventory pad to be located adjacent the shelves to be checked at all times and thereby greatly reduces the possibility of errors in tabulating the quantities of the various items being checked.

While a specific embodiment of an adjustable pad-support device for taking inventories of parts and the like has been disclosed in the foregoing description, it will be understood that various modifications within the spirit of the invention may occur to those skilled in the art. Therefore, it is intended that no limitations be placed on the invention except as defined by the scope of the appended claims.

What is claimed is:

1. A convertible support device comprising an upstanding frame structure including a pair of spaced side frames and cross bars extending between said side frames and secured thereto, a tray positioned upon the top of said side frames, a step member disposed intermediate said side frames contiguous to the lower end thereof and mounted on the latter for movement about an axis extending transverse of said upstanding frame from a retracted position to an extended position with respect to said upstanding frame, and a link positioned exteriorly of each of said side frames having one end pivotally connected to said tray and having the other end pivotally connected to the adjacent one of said side frames for mounting said tray for movement from its position of support on the top of said side frames to a position of support on said step member when the latter is in its extended position.

sition of support on the top of said side frames to a position of support on said step member when the latter is in its extended position.

2. A convertible support device comprising an upstanding frame structure having a downwardly and forwardly inclined top and including a pair of upstanding spaced side frames and cross bars extending between said side frames and secured thereto, a tray positioned upon the top of said upstanding frame, a step member disposed intermediate said side frames contiguous to the lower end thereof and mounted on the latter for movement about an axis transverse of said upstanding frame from a retracted position to an extended position with respect to said upstanding frame structure, and a link positioned exteriorly of each of said side frames having one end pivotally connected to said tray and having the other end pivotally connected to the adjacent one of said side frames for mounting said tray for movement from its position of support on the inclined top of said upstanding frame structure to a position of support on said step member when the latter is in its extended position.

3. A convertible support device comprising an upstanding frame structure having a downwardly and forwardly inclined top and including a pair of spaced side frames and cross bars extending between said side frames and secured thereto, a tray positioned upon the inclined top of said upstanding frame structure, a step member disposed intermediate said side frames contiguous to the lower end thereof and mounted on the latter for movement about an axis extending transverse of said upstanding frame structure from a retracted position to an extended position with respect to said upstanding frame structure, a link positioned exteriorly of each of said side frames having one end pivotally connected to the upper end of said tray and having the other end pivotally connected to the adjacent one of said side frames for mounting said tray for movement from its position of support on the inclined top of said upstanding frame structure to a position of support on said step member when the latter is in its extended position, and a strut member pivotally carried on said tray contiguous to the other end thereof and engageable with said inclined top to support said tray in an elevated position with respect to said top.
